UNITED STATES PATENT OFFICE

CHARLES R. KEERAN, OF EVANSTON, ILLINOIS, ASSIGNOR TO ROBERT N. BURTON, OF CHICAGO, ILLINOIS

MECHANICAL PENCIL

Application filed February 25, 1929. Serial No. 342,381.

This invention relates to mechanical pencils, and more particularly to pencils of the "propel"—"repel" type employing relatively long leads. The main object of this invention is to provide an improved operating mechanism, adapted to facilitate and insure engagement by the mechanism of a new lead when inserted through the tip. A further object is to provide an improved construction, wherein access may be had to the spare lead chamber without dismantling the main operating parts. It consists in certain features and elements of construction, in combination as herein shown and described, and 15 as indicated by the claims.

In the drawings:

Figure 1 is an enlarged axial section through a mechanical pencil embodying this invention shown broken to condense the 20 view; the plunger being shown at the limit of lead propelling movement and with the lead completely ejected.

Figure 2 is a longitudinal section through the pencil, with certain parts shown in full. 25 Figure 3 is an enlarged fragmentary longitudinal section of the lower portion of the pencil, showing the plunger at an intermediate position.

Figure 4 is a fragmentary longitudinal 30 section, showing the plunger and sleeve at the upper limit of movement.

Figures 5, 6, 7 and 8 are transverse sectional views taken substantially as indicated at lines 5—5, 6—6, 7—7 and 8—8 respectively, on Fig. 1.

Figure 9 is a perspective view of the eraser sleeve.

Figure 10 is a longitudinal sectional view 40 through a pencil of slightly modified construction, shown broken to condense the view.

The pencil illustrated in the drawings is of conventional design, having a tubular body, or barrel, 10, formed with a tapering tip portion, 11. This barrel may be formed 45 of any suitable material such as bakelite, celluloid, rubber, etc., and is provided with a longitudinal bore, 12, continuing into and correspondingly tapered in said tip portion, 11, to insure substantially uniform thickness

of wall. The end of said tapered portion 11, is internally threaded to receive the threaded shank, 13, of a metallic terminal tip portion, 14. Secured in the shank portion 13 is a bushing, 15, having a flange, 16, seated 55 against the end of the shank, and firmly secured in the bushing is a longitudinally extending guide tube, 17, concentrically disposed in the bore of the barrel and having its upper end closed and terminating adjacent 60 the upper end of the barrel. Said guide tube is formed with a longitudinal slot, 18, which extends from the bushing to adjacent the closed upper end of the tube, while the lower end portion of said guide tube is formed as 65 a clutch, composed of a plurality of outwardly movable spring fingers, 19, extending into the terminal tip portion, 14, below the bushing, 15, the terminal tip portion, 14, being chambered at 20 to provide clearance 70 for said fingers.

Longitudinally reciprocable in the guide tube is a cylindrical sleeve, 23, whose lower end is formed to frictionally grip a lead, 24, and adapted to act as a carrier therefor during its movement in either downward or upward direction. It is to be understood that the sleeve is made of any suitable metal and has its lead-engaging end provided with one or more longitudinal slits so that the portions intermediate the slits act as yielding tangs or clutch fingers for producing sufficient friction to retain a lead therein. Disposed in the sleeve is a plunger, 25, which primarily serves to impart axial movement 80 to the lead carrier sleeve, and to also effect the propelling through the tip terminal of the final portion of the lead, as will herein-after be described. Said sleeve is formed with a relatively short longitudinal slot, 26, which registers with the slot 18 in the guide tube 17, and through which slot projects a laterally extending driving lug, 27, of said plunger, which is cooperatively engaged 85 with an internally threaded rotary tubular member 28, concentrically surrounding said guide tube and sleeve and positioned in spaced relation to the inner wall of the barrel to form an annular chamber or magazine, 29, for the spare leads, 30. Thus the 90 95 100

slot 26 permits a limited range of axial movement of the plunger and sleeve with respect to each other. As will hereinafter more clearly appear, the rotary movement 5 of the tubular member 28 with respect to the barrel causes the plunger to be shifted axially therein, carrying the sleeve with it.

The plunger is normally yieldingly maintained retracted in the sleeve 23 with the 10 lead engaging end of the plunger, positioned a substantial distance within the lead engaging end of said sleeve, as shown in Fig. 3, and at this position the lug 27 is at the upper limit of the slot 26. The means for 15 yieldingly maintaining these parts in such relation, includes an extension, or tail piece, 33, on said plunger beyond the lug 27, which extension is slightly deformed to act as a spring—urged into frictional engagement 20 with the inside of the sleeve; the extreme end of said portion 33 being bent outwardly to form a hook terminal, 34, adapted to engage the end of the sleeve, as may be seen in Figs. 3 and 4. Thus, due to this resilient 25 connection, movement is imparted to the sleeve by the plunger in lead propelling direction, and in the reverse direction, the movement of the sleeve with the plunger is made positive by the lug, 27, engaging the 30 upper limit of the slot, 26.

It will now be apparent in connection with the drawings, that through the major portion of the lead propelling operation, the plunger and sleeve remain in the relation to 35 each other shown in Figs. 3 and 4, but during the propelling of the short remnant of the lead, the lower end of the sleeve encounters a stop shoulder, 37, in the tip terminal, 14, thus arresting its movement; and the 40 continued forced movement of the plunger by rotation of the tubular member 28 overcomes the reaction of the yielding spring portion 33, and the hook terminal 34, so that the plunger may continue its axial movement to propel the final or remaining portion of lead through the tip. An annular bead, 38, is formed on the sleeve adjacent 45 the lower end, and positioned for contactual engagement with the spring clutch fingers, 19, of the guide tube, when said sleeve abuts against the shoulder 37, in which position the clutch fingers yieldingly oppose retraction of the sleeve in lead retracting direction. However, when reloading by inserting 50 a new lead through the tip, the plunger is first backed up and retracted a short distance in the sleeve which is yieldingly held stationary by the clutch fingers engaging the bead 38, and the lead is then frictionally 55 engaged in the end of the sleeve; the desired extent of retraction of the plunger is indicated to the user when the spring portion 33 and terminal hook 34 snaps over the end of the sleeve.

60 If this action should not be noted, the

continued forced retraction of the plunger merely moves the sleeve farther into the barrel, causing the bead 38 to spread the fingers 19 outwardly and release the sleeve; the lead may then be inserted in the sleeve and further retraction of the sleeve and plunger draws the lead back in position for use. However, it may be frequently desirable to permit the sleeve to be yieldingly held at its 70 forward limit of movement so as to be capable of engaging the end of a relatively short piece of lead. It is to be understood that the internal diameter of the guide tube 17 at all points is of a size to insure clearance and unobstructed movement for the bead 38 of the 75 sleeve when telescoped therein. To prevent the sleeve and plunger from being shifted out of proper operating position with respect to each other when retracted to the upper limit in the guide tube, the end of the 80 sleeve is chamfered or beveled at 39 so that a portion of the sleeve projects beyond the hook terminal, 34, for encountering the 85 closed end of the guide tube, as shown in Fig. 4.

90 Although this construction is especially suitable for using relatively long leads, leads of various lengths, including short pieces, may be operatively inserted with the same facility as a long one; and the construction is such as to be ready to receive a lead at any position of the sleeve in the barrel provided only that the plunger has been retracted in the sleeve the necessary distance, as above 95 described.

100 The rotary tubular member, 28, extends a substantial portion of the length of the barrel, and is provided with bearing support at its lower end against the flange, 16, of the bushing; the upper end of said tubular member having an interlocking connection to the base wall, 41, of the tubular operating head, 42, by means of which the tubular member is 105 rotatable in the barrel. A washer or bushing, 43, is provided in the tip portion 11, serving to support and guide the tubular member and also serving as a bottom for the spare lead chamber. This washer has its peripheral edge serrated so as to be firmly 110 wedged in fixed position in the barrel. The 115 location of this washer is such as to insure against wedging of the leads in the tapered tip, and yet provide a relatively long spare lead chamber, of substantially the same 120 length as the longest lead that may be used in the mechanism.

125 Secured in the upper end of the barrel is a sleeve 45 having a portion extending out of the barrel and formed with a bead 46 loosely spun over an annular bead 47, formed as a continuation of the bottom wall 41 of the head 42. Thus the operating head is 130 swivelly locked to the barrel, forming a complete housing for the operating mechanism, which needs never to be disassembled

unless for repair purposes. The bottom wall 41 of the head is formed with an aperture, 48, affording access to the spare lead chamber; to complete the closure of the spare lead chamber and insure against breakage of the leads, 30, that might accidentally extend into and be caught by the aperture while the head and tubular member, 28, are being rotated relative to the barrel, I provide a boss, 49, substantially occupying the aperture, so as to present a relatively flush inner surface of the base wall 41 in the chamber. This projection 49 is formed as a depressed portion in the bottom of a tubular eraser sleeve, 50, which is adapted to be telescoped into the tubular operating head, 42, as shown in Fig. 1. This sleeve and tubular head are formed with cooperating tongue and groove connections to facilitate and insure correct registration of the boss with aperture 48. These include a pair of segmental inwardly extending annular beads, 51, formed in the wall of the tubular head adjacent the bottom, and spaced so as to form gaps of unequal extent. The lower end of the eraser sleeve 50 has cut-away portions, 52, correspondingly located, so that the sleeve may be seated with the remaining wall portions fitted between the beads 51 in the head in only one possible position, as may be seen in Figs. 5 to 7.

Telescoped in the eraser sleeve is an eraser socket, 55, of the spring prong type, in which is gripped an eraser, 56; the sleeve serving to compress the prongs into the eraser for securing it in any position of adjustment. The portion of the sleeve 50 extending beyond the head 42 is formed as a flange 57 to afford a convenient finger grip to remove the sleeve with the eraser and socket as a unit for access to the spare lead chamber. An ornamental cap, 58, is telescoped onto the operating head, completely enclosing the upper end of the pencil.

Fig. 10 illustrates a modified construction which is to be understood as being provided with substantially the same operating mechanism as above described. In this construction the operating head, 42^a, is swivelly connected to a ferrule, 61, which is threaded onto the upper end of the barrel 10^a, so that if desired, the entire head together with the threaded tubular member 28^a may be quickly and easily removed from the barrel. The lower end of the threaded tubular member is centered and supported in a bearing 16^b, disposed in the tip of the barrel and abutting against the flange, 16^a, of the bushing, 15^a. Concentrically disposed about the tubular member 28^a is a partition tube, 62, fixedly secured in the barrel in spaced relation to its inner wall to form a spare lead magazine 29^a opening at the upper end of the barrel. Reinforcing said tube 62 is a washer, 63, firmly lodged in the barrel, and

forming a bottom for the spare lead chamber.

I claim:—

1. In a mechanical pencil having a barrel and a tapered tip, a guide tube disposed in the barrel and extending a substantial length of the pencil, a sleeve disposed concentrically therein and mounted for reciprocation in said tube and having its lower end formed to frictionally engage a lead, and a plunger disposed in the sleeve and axially movable therewith in the guide tube in propelling a lead in either direction, said sleeve and plunger being interconnected to provide a limited range of axial movement of one part with respect to the other, said sleeve being dimensioned to engage a stop in the tip for limiting its axial movement in the propelling downward direction before the plunger movement is completed; said sleeve and guide tube having co-operating features, engageable at such limit of movement of the sleeve temporarily opposing upward movement of said sleeve to permit the plunger to first be withdrawn into the sleeve.

2. In the combination defined in claim 1, one of said co-operating features being adapted to yield radially to permit retraction of the sleeve in the guide tube upon forced axial movement of the plunger.

3. In the combination defined in claim 1, said co-operating features including a radially extending projection on the sleeve, and a radially movable resilient portion on the guide tube.

4. In the combination defined in claim 1, said co-operating features including an annular bead on the sleeve, and a plurality of radially yielding fingers at the lower end of the guide tube.

5. In a mechanical pencil having a barrel and a tapered tip provided with a rigid terminal portion through which a lead is guided, a guide tube disposed in the barrel and extending a substantial length of the pencil, a sleeve concentrically disposed in said tube and reciprocable therein and having its lower end formed to frictionally engage the lead, a plunger in the sleeve axially movable therewith in the guide tube for propelling a lead in either direction, means for causing such movement of the sleeve and plunger, said sleeve and plunger having a lost motion connection to permit limited axial movement of one part with respect to the other, said tip being formed with a stop to limit the axial movement of the sleeve in a downward direction and causing the sleeve to be arrested with its lead-engaging end within said tip, and means normally maintaining the plunger at the retracted limit of movement in the sleeve, and releasable when said sleeve encounters the stop in the tip so that the continued movement of said

110
115
120
125
130

plunger may feed the remnant of the lead through the terminal portion of the tip.

6. In a mechanical pencil having a barrel and a tapered tip provided with a rigid terminal portion through which a lead is guided, a guide tube disposed in the barrel and extending a substantial length of the pencil, a sleeve concentrically disposed in said tube and reciprocable therein and having its lower end formed to frictionally engage a lead, a plunger in the sleeve axially movable therewith in the guide tube for propelling a lead in either direction, means for causing such movement of the sleeve and plunger, said sleeve and plunger having a lost motion connection to permit limited axial movement of one part with respect to the other, said tip being formed with a stop to limit the axial movement of the sleeve 20 in downward direction and arresting the sleeve with its lead-engaging end within said tip, said plunger and sleeve being dimensioned so that at one limit of movement of the respective parts the lead-contacting end 25 of the plunger is retracted a substantial distance within the frictional lead-engaging end of the sleeve, and means for yieldingly maintaining said plunger in such relation to the sleeve, and adapted when the sleeve 30 is arrested by the stop in the tip to permit continued axial movement of the plunger beyond the lead-engaging end of the sleeve for propelling the remnant of the lead downwardly through said tip terminal.
- 35 7. In the combination defined in claim 6, said yielding means including a resilient hook portion on said plunger adapted to engage against the upper end of the sleeve.
8. In a mechanical pencil having a barrel 40 and a tapered tip, a guide tube disposed in the barrel and extending through a substantial part of the length of the pencil, the upper end of said tube being formed to provide a stop, a sleeve concentrically disposed in 45 said tube and reciprocable therein and having its lower end formed to frictionally engage a lead; a plunger in said sleeve, axially movable therewith, in said guide tube for propelling a lead in either direction, means 50 for effecting such movement, said sleeve and plunger being inter-connected to permit a limited range of axial movement with respect to each other, and means normally tending to retain said plunger at the retracted limit of movement in the sleeve, said 55 means including an outwardly extending resilient hook portion at the upper end of the plunger and adapted to engage the upper end of the sleeve; said upper end of the 60 sleeve being beveled to provide a portion projecting beyond said hook portion and adapted to abut against the stop in the guide tube for limiting the retraction therein of the sleeve.
- 65 9. In a mechanical pencil, a barrel, a

threaded tubular member concentrically disposed in the barrel, a slotted guide telescoped within said threaded member and rigidly secured to the barrel adjacent its lower end, a head rotatively engaged with the barrel and fixed to the threaded tube for turning it, a lead-propelling plunger longitudinally movable in the slotted guide and having a driving lug projecting through the slot thereof for engagement with the threaded tube, together with a lead-gripping sleeve carried on the plunger and slidably longitudinally through a limited range thereon, said sleeve being positively engaged with the plunger at the limits of such range and extendable beyond the lower end of the plunger for engaging a lead, and stop means in the barrel for arresting movement of the sleeve adjacent the lower end of the barrel and permitting the plunger to slide through the sleeve in lead-propelling direction.

10. In the combination defined in claim 9, stop means fixed with respect to the barrel, positioned to hold the sleeve at its lower limit therein until the plunger is retracted 90 within the lower end of the sleeve.

11. In a mechanical pencil having a barrel provided with a longitudinal bore, a tube supported concentrically in said bore in spaced relation to form an annular spare lead chamber, a tubular head having a bottom wall rigidly secured to the upper end of the tube and disposed to close the end of the chamber, said bottom wall being provided with an aperture affording access to the chamber, and a sleeve telescopically associated with the head and having a bottom portion provided with a boss formed to extend into and seat in said aperture to complete the closure of the spare lead chamber.

12. In the combination defined in claim 11, said boss occupying the entire aperture and presenting a surface substantially flush with the surface of said bottom wall which faces toward the chamber.

13. In the combination defined in claim 11, means for positively registering the boss of the sleeve with the aperture of the head as the former is telescoped into the latter.

14. In the combination defined in claim 11, said tubular head and sleeve having inter-engaging tongue-and-groove features for insuring registration of the boss with the aperture as the sleeve is telescoped into the head.

15. In a mechanical pencil, a barrel, a tubular member rotatably supported concentrically in the bore of the barrel in spaced relation to form an annular spare lead chamber, a tubular head having a bottom wall rigidly secured to the tubular member, and positioned to close the end of the spare lead chamber, said head and barrel having a swivel connection whereby said head and tubular member are rotatable together with

- respect to said barrel, said bottom wall of the head having an aperture therein affording access to said lead chamber, a sleeve telescopically associated with the head, provided with a bottom portion having a boss adapted to register with the aperture for completing closure of said spare lead chamber, means for insuring registration of said boss and said aperture when the sleeve is telescoped into the head, and a yieldable eraser gripping socket adapted to be telescoped into said sleeve, said sleeve serving to compress said eraser socket for gripping its eraser in any position of adjustment.
16. In a mechanical pencil a barrel, a threaded tubular member concentrically disposed in said barrel, a head rotatively engaged with the barrel and fixedly secured to said tubular member for turning it, a slotted guide telescoped within said threaded tubular member and rigidly secured to the barrel adjacent its lower end, a lead-propelling plunger longitudinally movable in the slotted guide and having a driving lug projecting through the slot thereof for cooperative engagement with the threaded tubular member, a lead-gripping sleeve carried on the plunger and axially movable therewith in the slotted guide, said sleeve and plunger having a lost motion connection to permit limited axial movement of one part with respect to the other, stop means in the barrel for arresting movement of the sleeve in downward direction when the latter arrives adjacent the lower end of the barrel so that continued movement of the plunger permits the same to slide through the sleeve in feeding the remnant of the lead therethrough, and means engageable when said sleeve encounters said stop for yieldingly opposing upward movement of said sleeve to permit the plunger to be first retracted into the sleeve.
17. In a mechanical pencil having a barrel and rotatable head and a lead propelling mechanism in the barrel, said mechanism consisting of a slotted guide tube within a spiral member and a plunger in the slotted tube having engagement with the spiral member through the slot, together with a lead holding sleeve telescoped over said plunger and slidable therewith in the slotted tube, said spiral member being rigidly connected to said head and rotatable in the barrel, and said slotted tube being rigidly mounted in the barrel, means permitting limited telescopic movement between the plunger and the sleeve, and means independent of the spiral for holding the plunger and sleeve in normal working position with the end of the plunger retracted within the sleeve.

CHARLES R. KEERAN.
